O. F. BALTZLEY.

APPARATUS FOR DRILLING AND REAMING AND COUNTERSINKING.

APPLICATION FILED MAR. 5, 1920.

1,362,913.

Patented Dec. 21, 1920.

Inventor:

Oren F. Baltzley,

Spear, Middleton, Darlas and Hall
Attorneys.

UNITED STATES PATENT OFFICE.

OREN F. BALTZLEY, OF HAGERSTOWN, MARYLAND, ASSIGNOR TO THE LIBERTY TOOL COMPANY, OF BALTIMORE, MARYLAND, A CORPORATION OF MARYLAND.

APPARATUS FOR DRILLING AND REAMING AND COUNTERSINKING.

1,362,913.

Specification of Letters Patent. Patented Dec. 21, 1920.

Original application filed April 3, 1919, Serial No. 287,259. Divided and this application filed March 5, 1920. Serial No. 363,525.

To all whom it may concern:

Be it known that I, OREN F. BALTZLEY, a citizen of the United States, and resident of Hagerstown, State of Maryland, have invented certain new and useful Improvements in Apparatus for Drilling and Reaming and Countersinking, of which the following is a specification.

My invention is an improvement upon portable apparatus for drilling, reaming, or countersinking and one object of the invention is to provide such an arrangement and construction of parts as will give large capacity to the machine by enabling it to be used in situations where machines as heretofore constructed could not be employed and is a divisional application of my pending application 287,259, now Patent #1,352,646.

A prior form of portable machine is that shown in the United States patent of Dif- fendall No. 1249045, December 4, 1917, in which a cutting tool and its driver are carried by a bracket or support mounted on a frame member or bar which has fixed thereon at its end a cylinder in which works a piston forming a work feeding or holding device to feed the work relative to the frame bar or member and the cutting device carried thereby, when said piston is operated by fluid pressure let into the cylinder.

An objection exists to this cylinder and piston arranged at the end of the frame and beyond the point where the work is done. There are work pieces of such form or of such location relative to other parts of the structure with which they are associated that the cylinder and its piston cannot be fitted to because of lack of space.

I therefore dispense with the cylinder and piston at the end of the main frame member or bar and instead I provide a feed foot or what is called in the trade a "crow-foot" fixed to the frame member or bar to engage and hold or feed the work piece. This frame member or bar and the tool are relatively movable, the frame member and the tool carrier having a sliding connection with each other. The relative movement is effected by a cylinder and piston operated by fluid pressure, the piston being connected to one of the said parts, *i. e.*, either the main frame

member or the tool carrier and the cylinder being connected to the other so that when the fluid pressure is on there will be a relative movement between the main frame member and the tool carrier and therefore the feed foot on the frame member or bar will feed the work piece to the tool, if the latter is held at one position, or in case the work piece is of such a character that it must remain stationary then the feeding movements take place at the tool carrier.

In either case there is a relative movement between the main frame carrying the feed foot and the tool carrier, the fluid pressure operated means acting in part on the tool carrier and in part on the main frame or bar, and not acting on the work piece directly so that both the cylinder and piston can be located apart from the point where the work piece is to be held or fed.

This "crow-foot" or feed foot extends laterally from the frame bar and lies opposite the tool and it is of such restricted size that it can be located in positions, such for instance as in narrow spaces between flanges where the terminal cylinder and piston above mentioned cannot be placed and thus the machine has a wider range of use than machines of the prior form.

The invention consists in the features and combination and arrangement of parts hereinafter described and particularly pointed out in the claims.

The drawing is a side view of a drilling machine embodying the invention.

In this drawing the bar or frame member is shown at *i*, having the feed foot *p*³ mounted thereon, its immediate support being a bolt *p*⁵ adjustable in a vertical slot *p*⁴ of a bracket clamped to the bar by a bolt *p*⁶ operated by a handle *p*². This feed foot is in the form of a fork to permit the passage of the drilling tool.

The motor indicated in dotted lines at *b* is supported at one end upon a bolt or stem *c*, having a threaded end to engage a suitable portion of the motor casing. The bolt has a hand wheel *d* by which it may be turned. The bolt is mounted in the arm *e*³ of a frame member or bracket lying to one side of the axis of the motor, the frame being slidably mounted on the carrier bar *i*.

The bracket has a pivoted arm e^4 held by a link e^5 and nut e^6 by which it may be adjusted to support the front end of the motor. The parts s , s'' , s^2 may be used for ejecting the tool from the motor.

5 The tool or drill is shown in dotted lines at l and the work piece at w .

The bracket e^3 with the tool and the bar i with the feed foot p^8 are moved relative to each other by a cylinder k^3 and piston k^4 . The cylinder is connected to the bar i rigidly though adjustable thereon and the piston is rigidly connected to the bracket e^3 by its piston rod k^5 . The pressure fluid is introduced into the cylinder by a conduit k^6 through the piston rod k^5 from an inlet k^7 .

10 The piston and cylinder will give relative movement to the carrying bar i and the bracket e^3 in either direction for advancing 20 the drill to and through the work piece w or for withdrawing it.

15 A clamp q may be used for clamping the work piece between itself and the feed foot, p^8 . This clamp is adjustable on the bar i and may be set in any position by the clamp 25 bolt q' operated by a suitable handle. At r is shown a stop which may be fixed to the bar i in different positions to limit the depth to which the drill will penetrate the work 30 piece.

30 The whole apparatus is portable. The cylinder and piston arrangement k^3 , k^4 is on the same side of the frame bar as the bracket e^3 and is on the opposite side of said bracket 35 from the point at which the feed foot is located. The arrangement of parts is such that the apparatus is of minimum width and is susceptible of use in close situations.

I claim:—

1. A portable drilling apparatus comprising a bar, a feed foot attached thereto, a bracket slideable relative to the bar and carried thereby, a motor and tool mounted in the bracket, a piston and cylinder arranged at the opposite side of the bracket 45 from where the feed foot is located, one of said parts being connected with the bracket and the other with the carrying bar and means for introducing pressure fluid into the cylinder, substantially as described. 50

2. A portable drilling apparatus comprising a bar, a feed foot attached thereto, a bracket slideable relative to the bar and carried thereby, a motor and tool mounted in the bracket, a piston and cylinder arranged 55 at the opposite side of the bracket from where the feed foot is located, said piston having its rod connected with the bracket and the cylinder mounted fixedly on the said rod, substantially as described.

3. A portable drilling apparatus comprising a bar, a feed foot attached thereto, a bracket slideable relative to the bar and carried thereby, a motor and tool mounted in the bracket, a piston and cylinder arranged 65 at the opposite side of the bracket from where the feed foot is located, one of said parts being connected with the bracket and the other with the carrying bar and means for introducing pressure fluid into 70 the cylinder, both the piston and cylinder being on the same side of the rod as the bracket, substantially as described.

In testimony whereof I affix my signature.

OREN F. BALTZLEY.
